CLAIM

The ornamental design for a spout portion, as shown and described.

DESCRIPTION

FIG. 1 is a perspective view of a spout portion of the new design;

FIG. 2 is a left side elevational view of the spout portion of FIG. 1;

FIG. 3 is a front elevational view of the spout portion of FIG. 1;

FIG. 4 is a top plan view of the spout portion of FIG. 1;

FIG. 5 is a right side elevational view of the spout portion of FIG. 1;

FIG. 6 is a rear elevational view of the spout portion of FIG. 1; and,

FIG. 7 is a bottom plan view of the spout portion of FIG. 1.

The portions of the Figures shown in broken lines are not part of the claimed design and are for illustration only.
